(Cl. D81—10)

To all whom it may concern:

Be it known that I, Matthew F. Orr, a citizen of the United States, residing in Kansas City, in the county of Jackson and State of Missouri, have invented a new, original, and ornamental Design for a Deep Fat Fryer, of which the following is a specification, reference being had to the accompanying drawing, forming part thereof, in which:

Fig. 1 is an end elevational view of a deep fat fryer embodying my new design,

Fig. 2 is a side elevational view of the deep fat fryer, and

Fig. 3 is a top plan view of the deep fat fryer.
I claim:

The ornamental design for a deep fat fryer, substantially as shown.
